UNITED STATES PATENT OFFICE.

THOMAS A. WALTON, OF SCRANTON, PENNSYLVANIA.

SWIMMING-INSTRUCTING MACHINE.

Application filed December 6, 1923. Serial No. 679,042.

The present invention relates to a swimming instructing machine or apparatus and has for its principal object to provide means whereby a swimming pupil may learn the correct movement of the limbs utilized in swimming and at the same time exercise and thereby strengthen the desired muscles.

An important object of the invention is to provide an apparatus of this nature which is adjustable so that it may be utilized by different pupils regardless of their size.

With the above and numerous other objects in view as will appear as the description progresses, the invention resides in certain novel features of construction, and in the combination and arrangement of parts as will be hereinafter more fully described and claimed.

In the drawing:

- 20 Figure 1 is a top plan view of the apparatus embodying my invention;
Figure 2 is a side elevation thereof;
Figure 3 is a detail side elevation on an enlarged scale showing the arm-exercising 25 crank; and

Figure 4 is a detail elevation on an enlarged scale of the leg-exercising crank.

Referring to the drawing in detail it will be seen that the apparatus includes a forward support consisting of two standards 1 and a rearward support including two standards 2. These supports are adjustably connected to each other by means of plates 3 and 4, the plate 3 being provided with 30 marginal over-hanging flanges 5 for receiving the edges of the plate 4 as is indicated to advantage in Figure 1 whereby these two plates may be extended or retracted in relation to each other thus moving the standards 35 1 and 2 away from or toward each other.

A platform 5 is supported on the standards 1 and extends rearwardly toward the standards 2. A block 6 is positioned on this platform by means of threaded studs 7 40 passing through the slot 8 thereof. Thus by loosening the nuts 9 on the studs 7 the block 6 may be adjusted longitudinally of the platform. This block 6 is so formed as to comfortably support a person in a substantially prone position as shown in Figure 50

2. The platform 5 includes a plate or extension 11 extending transversely thereof and supported on the upper ends of the standards 1. This plate is provided with 55 longitudinally extending slots 12. A journal bracket 13 is associated with each

slot as is indicated to advantage in Figure 3 and a bolt 14 is associated therewith so that the bracket may be locked in any longitudinal adjusted position on the plate by 60 means of a nut 15. A shaft 16 is journaled through each journal bracket 13 and in a similar journal 13' provided on the plate 3. A crank 17 is disposed on the upper end of this shaft above the plate 11 and is provided with a longitudinally extending slot 18. A shank 19 of a knob 20 pierces the slot 18 and is adapted to be held in adjusted position therein by means of a nut 21. A sleeve 22 is disposed about the shank so that the same 70 may be readily rotated at all times in respect to the crank 17.

The rear standard 2 supports the plate 4 intermediate their ends and the plate 24 at their upper ends. The plate 4 is provided with longitudinally extending slots 25 for receiving journal brackets 26 which are similar in construction to journal brackets 13. Shafts 27 are journaled through these brackets 26 and in similar brackets longitudinally adjustable on plate 4 similar to brackets 13'. Sprocket wheels 28 are rotatable with the shafts 27 so that chains 29 may be trained thereover and also over sprocket wheels 30 on the shafts 16 so that one shaft 85 16 will operate in unison with one shaft 27. Each shaft 27 is provided with a crank 31 similar in construction to the crank 17 and a foot-receiving member 32 is adjustably mounted thereon. As is shown to advantage 90 in Figure 4 the depending stems 33 of these foot-receiving members 32 are mounted in sleeves 34 carried in the slots of the cranks 31 and held in place by nuts 35. Thus the members 32 are free to rotate but are nevertheless held in any desired adjusted position 95 in relation to the crank. These members 32 are substantially cup-shaped in formation and are provided in their interior with suitable padding 36. The shafts 16 are also provided with sprocket wheels 27 disposed above sprockets 30 so that a chain may be trained thereover for operation of the shafts 16 in unison with each other but in opposite 100 directions, this being accomplished by merely crossing the chains.

The pupil lies in a prone position resting on the block 6 as indicated in Figure 2 and grasps the knobs 20 with his hands and places his feet in the members 32. He then 110 rotates the cranks 17 in imitation of the usual breast stroke and it will be seen im-

mediately that this apparatus will cause him to move his arms and legs in proper unison with each other in imitation of the breast stroke whereby he will be accustomed 5 to the motion and will strengthen those muscles necessary in swimming this stroke. It is also evident that the apparatus may be adjusted to accommodate persons of different sizes by the various adjustments described; thus the plates 3 and 4 may be 10 adjusted to accommodate the height of the person and the cranks may be adjusted to accommodate the length of his limbs.

From the foregoing description taken in 15 connection with the accompanying drawings, the advantages of the construction and the method of operation, will be readily understood by those skilled in the art to which the invention appertains, and while I have 20 described the principle of operation together with the device which I now consider to be the best embodiment thereof I desire to have it understood that the device shown is merely 25 illustrative and that such changes in the details of construction and in the combination and arrangement of parts may be resorted to without departing from the scope of the invention as hereinafter claimed.

What is claimed is:

30 1. An apparatus of the class described including a pair of supports, extension plates secured adjacent the lower ends of the supports and arranged for adjustable connection, a rearwardly projecting platform secured adjacent the upper end of the forward support, means mounted on the platform for supporting a body in prone position, arm exercising cranks rotatably mounted at the upper extremity of the forward support, leg exercising cranks mounted on the upper end of the rear support, and means whereby the cranks may be operated uniformly.

45 2. An apparatus of the class described including a pair of supports arranged in spaced relation, engageable extensions formed on the supports adjacent the lower ends arranged for adjustable connection, a rearwardly extending platform formed adjacent the upper end of the forward support, a rest block mounted on the platform for supporting the body in prone position, arm exercising cranks rotatably mounted in the upper end of the forward support, engaging knobs 55 movably mounted in the cranks adjustable to vary the radius of the arc described by rotary movement of the knobs, leg exercising cranks rotatably mounted in the upper end of the rear support, foot engaging cups 60 adjustably mounted on the leg exercising cranks arranged to vary the radius of the circle described by the cups, and means for operating the cranks simultaneously.

65 3. An apparatus of the character described including a pair of supports, a pair of en-

gageable extensions carried by the supports and arranged for longitudinal adjustment of the supports, arm exercising cranks rotatably mounted in the upper end of the forward support, leg exercising cranks rotatably mounted in the upper end of the rear support, means for operating the cranks at a uniform rate of speed, a platform extending rearwardly from the upper portion of the front support, and a rest block adjustably mounted on the platform to permit longitudinal adjustment of the block relative to the cranks.

4. An apparatus of the character described including a pair of supporting members, engageable extensions secured adjacent the lower ends of the supporting members arranged for longitudinal adjustment of the supports, a platform mounted in an elevated position on the forward support and arranged to support a body thereon, rotatable arm exercising cranks mounted on the platform, an extension plate mounted on the rear supporting member, rotatable leg exercising cranks mounted in the said extension plate, 90 the said arm exercising cranks being arranged in an elevated position relative to the leg exercising cranks for convenient operation, and means for simultaneously rotating the cranks at a uniform speed.

5. An apparatus of the character described including a pair of spaced supporting members, engageable extensions secured to the supporting member and arranged for adjustment of the supporting members to or 100 away from each other, a platform mounted on the forward supporting member including a transversely extending plate and a rearwardly extending plate formed at the intermediate portion of the platform, arm 105 exercising cranks rotatably mounted on the transverse plate of the platform and arranged for lateral adjustment, a rest block adjustably mounted on the rearwardly extending plate of the platform, a transversely 110 extending plate secured upon the rear supporting member, leg exercising cranks rotatably mounted upon the said transverse plate on the rear supporting member arranged for lateral adjustment, and means 115 for operating the said cranks at a uniform rate of speed.

6. An apparatus of the character described including a pair of supporting members connected for longitudinal adjustment, arm 120 exercising cranks mounted in the forward supporting member, leg exercising cranks mounted on the rear supporting member, means for laterally adjusting the said arm and leg exercising cranks including crank 125 supporting brackets arranged for lateral movement on the supporting members, and means for operating the cranks at a uniform rate of speed.

7. An apparatus of the character described 130

including a pair of spaced supports composed of a pair of laterally spaced standards, extension plates secured adjacent the lower ends of the supporting standards and slidably engageable for longitudinal adjustment of the supports, the forward standards being longer than the rear standards, a platform secured upon the forward standards including a transversely extending crank plate having longitudinal slots formed therein, a rearwardly extending plate connecting with the central portion of the transverse plate and having a longitudinal slot therein, crank supporting brackets adjustably mounted in

the slot of the transverse plate, arm exercising cranks rotatably mounted in the said brackets, a rest block adjustably connected with the rearwardly extending platform plate, a second transversely extending plate secured upon the rear support standards and having longitudinal slots formed therein, crank supporting brackets adjustably mounted in the said plate slots, arm exercising cranks rotatably mounted in the brackets, and means for rotating the said arm and leg exercising cranks simultaneously. ¹⁵ ²⁰ ²⁵

In testimony whereof I affix my signature.

THOMAS A. WALTON.
